UNITED STATES PATENT OFFICE.

FREDERICK HARVEY RAPLEY, OF ALLEGHENY, PENNSYLVANIA, ASSIGNOR
TO PRESSED STEEL CAR COMPANY, OF PITTSBURG, PENNSYLVANIA, A
CORPORATION OF NEW JERSEY.

RAILWAY-CAR.

SPECIFICATION forming part of Letters Patent No. 732,113, dated June 30, 1903.

Application filed April 15, 1902. Serial No. 103,043. (No model.)

To all whom it may concern:

Be it known that I, FREDERICK HARVEY RAPLEY, a subject of the King of Great Britain, residing at Allegheny, Pennsylvania, 5 have invented new and useful Improvements in Railway-Cars, of which the following is a specification.

These improvements relate chiefly to railway-cars in which the body and underframing are made of pressed sheet metal, preferably steel, although structural metal may be employed wholly or in part, as desired; and the object of the improvements is to produce a light, strong, cheap, and easily-constructed 15 car which is especially suitable for the transport of coal and other material in bulk.

The improvements are in the accompanying drawings shown embodied in a four-wheeled car or wagon especially suitable for 20 the transport of coal or other material in bulk.

Figure 1 is a part-sectional side elevation; Fig. 2, a sectional end elevation; Fig. 3, an end elevation, and Fig. 4 a plan in which the lower half is shown with the floor-plates removed in order to show the underframing more clearly. Figs. 5 to 9 are sectional views of various places of junction of the parts drawn to a larger scale, Fig. 5 showing the junction of a sole-bar and a floor-plate, Fig. 30 6 showing the junction of a floor-plate and a side wall, Fig. 7 showing the junction of a floor-plate, a cantaliver-bracket, and a side wall, Fig. 8 showing the junction of a transverse stiffener and a center sole-bar with two 35 floor-plates riveted thereto, and Fig. 9 being a horizontal section of the side doors where they meet.

The two outer longitudinal supporting-sills or sole-bars *a* under the floor are made of L-40 section with the bottom flange bent outwardly. The two middle longitudinal supporting-sills or sole-bars *b*, of similar L-section, run parallel in the middle part and are splayed off toward the buffers at each end for 45 taking part of the end thrust against the buffers. The floor-plates *c* are fixed between the middle sole-bars *b* and between them and the outer sole-bars *a*, as shown clearly in Fig. 4, and have downturned flanges on all four 50 edges for joining by riveting to the sole-bars

a and *b* and to each other, as shown in Figs. 5 and 8, and also to the upstanding sides *f* of the car, as shown clearly in Fig. 6, and to the ends of the car, as shown in Fig. 3. The floor is thus rendered very strong and light and 55 has no rivet-heads inside that would interfere with the use of the coal-shovel, and the sole-bars *a* and *b* are at the same time reinforced by the flanges of the floor-plates riveted to them. The transverse flanges of the 60 floor-plates not only act as girders to support the floor, but have also the function of tying the sole-bars *a* and *b* strongly together. The floor-plates on the sole-bars *a* are at intervals supported by and riveted to cantaliver-brackets *d*, of sheet-steel, which are riveted to the outer sole-bars *a* and are formed with a pressed-up flange all around on one side. The outer downturned flanges of the floor-plates enter between the end of the brackets *d* and 65 the outer side wall *f*, as shown clearly in Fig. 7.

The upstanding sheet-steel ends *e* of the car consist of plates, three in this example, which are flanged outwardly on the two sides and flanged inwardly along the bottom, the 70 flange then running up slantingly (see Figs. 1, 2, and 3) from the point where it leaves the flange of the side sole-bars *a* on each side to the place where it meets the flange of the lateral floor-plate *c*. The end sheets are ap- 75 pertured for the passage of the draw-bars. The upstanding sheet-steel sides *f* consist of plates flanged outwardly as to the end sheets and middle sheets on one vertical edge and as to the intermediate sheets flanged on two 80 vertical edges for the purpose of stiffening, and are also riveted to the floor-plate flanges, thus doing away with rivet-heads on the inner sides of the car. Along the top these side walls and end walls are stiffened by means of 85 angle section-bars *g*. L-shaped transverse stiffeners or struts *h* are provided, which have pressed-up end flanges and are riveted to the under side of the middle sole-bars *b* and by their end flanges to the inner sides of the 90 side sole-bars *a*.

j are two door-posts made of triangular plates flanged all around toward the ends of the car. The bottom flanges of these posts are riveted to the floor, the upright outer 95

flange is riveted to the side of the car, and the top flange is riveted to the longitudinal stiffening-bar *g*. The two doors *p* are hinged to the posts *j* and meet in the middle, where 5 the right-hand door has a closing-strip *g* riveted thereto. The doors are flanged on all four sides outwardly. The doors are held together by a lever-latch *k*, to which is jointed a vertical bolt *l*, the lower end of which enters a staple on the outer side of the car. To 10 this bolt is jointed one arm of a lever-handle *m*. By depressing the handle the bolt is raised out of its staple and the latch *k* from its staples on the two doors, so that the doors 15 can be swung open toward the outside, or, vice versa, to secure the doors when closed the handle *m* is raised, so that the latch *k* and the bolt *l* are simultaneously inserted in their staples. The doors are pressed up into 20 buckled panel shape for the sake of stiffness. The buffers are made in an upper and a lower half *n*, pressed out of sheet-steel, and with joining flanges along the middle and with continued upturned end flanges for fixing to 25 the base-plate *r*, which is bolted to the end sill or head-stock of the car. A hole *o* is provided in each half for inspecting the state of the spring inside and for draining.

The ends of the sole-bars *a* and *b* are tied 30 together by a reinforcing-piece *s* inside and by the angular reinforcing-piece *t* outside. The pressed-steel horn-plates *u* are flanged up along two edges, as shown in Figs. 1 and 4, and are riveted to the outer sole-bars *a*. 35 They have guide-pieces *v* riveted on, which are united by the tie-bar *w*.

I claim—

1. A car, having two central L-shaped sole bars or sills with the flange below, and which 40 are splayed toward the buffers, two similar parallel outer sole-bars, and floor-plates flanged downwardly on all four sides, riveted to the said central and outer sole-bars and to the side walls and end walls, substantially as 45 set forth.

2. A car, having two central L-shaped sole bars with the flange below, and which are splayed toward the buffers, two similar parallel outer sole-bars, floor-plates flanged downwardly on all four sides, riveted to the said 50 central and outer sole-bars and to the side walls and end walls, cantaliver-brackets riveted to the floor-plates outside of the outer sole-bars and riveted to the said sole-bars and

to the side walls, and transverse stiffeners 55 riveted to the sole outer and inner bars, substantially as set forth.

3. A car, having two central L-shaped sole-bars with the flange below and which are splayed toward the buffers, two similar parallel outer sole-bars, floor-plates flanged downwardly on all four sides, riveted to the said 60 central and outer sole-bars, cantaliver-brackets riveted to the floor-plates, to the side walls and to the outer sole-bars, upstanding side 65 walls made of plates flanged outwardly along the sides where they are riveted together, and end walls made of plates flanged outwardly along the sides and riveted together and riveted to the side walls, the plates of the said 70 end walls being flanged inwardly along the bottom and slanting from the side sole-bar to the lateral floor-plate, substantially as set forth.

4. A car, having its side walls and end walls 75 made of pressed plates provided with vertical flanges on adjacent outer edges only and riveted together by such outer vertical flanges, in combination with an angle section-bar riveted along the top of the side walls and end 80 walls, substantially as set forth.

5. A car, having a side wall interrupted in one place, a door-post on each side of the space riveted to the side wall and to the bottom of the car, pressed sheet-metal folding 85 doors hinged to the door-posts and provided with staples, a latch pivoted to one door, a vertical bolt jointed thereto, a staple therefor below on the side of the car, and a lever-handle jointed to the door and to the bolt for operating the latch and the bolt simultaneously, 90 substantially as set forth.

6. A car, having a side wall interrupted in one place, a door-post on each side of the space made of pressed sheet metal with flanges 95 all around said posts riveted to the side wall and to the bottom of the car, sheet-metal folding doors hinged to the door-posts, and a bolt-and-latch device for holding the doors firmly in the closed position, substantially as 100 set forth.

In testimony whereof I have signed my name to this specification in the presence of two subscribing witnesses.

FREDERICK HARVEY RAPLEY.
